UNITED STATES PATENT OFFICE

JOHN C. SCOVEL, JR., OF CHICAGO, ILLINOIS, ASSIGNOR TO THE CREAMERY PACKAGE MFG. COMPANY, OF CHICAGO, ILLINOIS, A CORPORATION OF ILLINOIS

REFRIGERANT-COMPRESSOR-CONTROL MANIFOLD

Application filed October 9, 1928. Serial No. 311,327.

The invention relates to the groups of devices commonly associated with a refrigerant compressor for controlling the flow of refrigerant fluid to and from the compressor, and more particularly relates to the compact structural arrangement of the several devices for convenient manipulation.

In mechanical refrigerating apparatus, there are commonly installed with the compressor a pair of hand valves respectively controlling the suction line and discharge line connections to the compressor, a pair of valve-controlled by-pass connections respectively from the compressor discharge port to the suction line and from the compressor suction port to the discharge line, a device for trapping oil out of the discharged refrigerant with means for returning it to the compressor, a device for trapping pipe scale out of the refrigerant returned through the suction line, and a pair of gauges respectively indicating pressures in the suction line and discharge line. These several devices ordinarily comprise independent structural units with numerous pipe connections and fittings, forming a confusing arrangement for manipulation by an operator, and occupying a considerable space about the compressor.

The object of this invention is to provide a unitary control manifold structure in which is incorporated the functions of all of the above enumerated devices, of compact form, and in arrangement readily discernible and easy of manipulation. Another object is to provide such a manifold of simple construction wherein many of the pipe and fitting joints ordinarily required are avoided. Further objects and advantages will be apparent in the following description of a preferred embodiment of the invention illustrated in the accompanying drawings.

In the drawings, Fig. 1 represents a side view in elevation of the structure of the invention. Fig. 2 is a sectional side elevation taken on the plane of the line 2—2 in Fig. 3. Fig. 3 is a sectional front elevation taken on the planes of the irregular line 3—3 in Fig. 2. Fig. 4 is a sectional side elevation taken on the plane of the line 4—4 in Fig. 3. Fig. 5 is a sectional plan taken on the planes of the

irregular line 5—5 in Fig. 4. Fig. 6 is a partial view in front elevation taken on the plane of the line 6—6 in Fig. 2.

Referring to the drawings, the reference numerals 1 to 6 inclusive indicate respectively the front, rear, right side, left side, top, and bottom walls of a hollow body structure, having within the lower portion a horizontal full partition wall 7, and within the upper portion a horizontal half partition wall 8. A laterally extending vertical partition wall 9 divides the space between the bottom wall 6 and the partition 7, and another laterally extending vertical partition wall 10 joins the inner edge of the half partition 8 and the top wall 5. The several walls indicated form within the body structure an upper rear chamber 11, a lower rear chamber 12, a lower front chamber 13, and an intermediate chamber 14 extending upwardly in its front portion to the top wall 5.

A flanged tubular fitting 15, preferably integral with the rear wall of the body, communicates through opening 16 with the chamber 11, and is adapted for connection with the discharge port of the compressor. A similar fitting 17, communicating through opening 18 with the chamber 12, is adapted for connection with the suction port of the compressor. A port opening 19 through the partition 10 establishes communication between the chamber 11 and the upper portion of the intermediate chamber 14, the latter communicating with the discharge line to the refrigerant condenser through a pipe connection 20 entering the upper wall of the body structure. A port opening 21 through the partition 9 establishes communication between the rear chamber 12 and the front chamber 13, the latter communicating with the suction line from the refrigerant expansion coils through a pipe connection 22 entering the side wall 4 of the body structure.

The ports 19 and 21 are controlled respectively by a pair of stop valves 22 and 23 of conventional construction for use with refrigerant gas and comprising in each case a valve disc 24 adapted to be operatively seated upon marginal seats provided about the respective ports, and having guide wings 25 extending

into the port openings. Each valve disc 24 is supported on a stem 26 carrying a hand wheel 27, the stem being operatively supported in a conventional flanged valve bonnet 28 extending through an opening 29 in the front wall of the body structure and removably secured thereto as by bolts 30.

The intermediate chamber 14 is designed to trap out the compressor lubricating oil carried over by the compressed refrigerant gas discharged through the port 19 before the gas passes to the discharge line through the connection 20. The oil trapping function is aided by a baffle plate 31 extending across the upper extremity of the chamber 14 between the port 19 and the outlet connection 20. Thus, the high pressure gas passing the port 19 strikes either the plate 31 or the outer walls of the chamber before escaping through the connection 20, such impact effecting the deposit of the oil particles carried by the gas within the chamber 14. The accumulations of oil in the chamber 14 may be discharged periodically into the suction chamber 12 through a passage 32 opening through the partition wall 7 and controlled by a conventional hand valve 33 having its valve disc 34 positioned in the passage 32. From the suction chamber 12, the oil is drained back to the compressor crank case through a pipe connection indicated at 35.

The lower front or antechamber 13 accommodates a scale trap comprising a tubular screen 36 positioned in continuation of the suction line inlet connection 22 and supported in suitable openings in the opposite lateral walls 3 and 4 of the body, as indicated at 37 and 38. The tubular screen 36 serves to retain any scale entering the antechamber 13 from the suction line 22, and the screen may be endwardly removed for cleaning through the opening 38. The screen is normally held in position, and the opening 38 outwardly sealed, by a removable cap 39 secured to the body wall as by cap screws 40.

A safety by-pass connection is provided between the high-pressure discharge chamber 11 and the low-pressure or vacuum antechamber 13—the latter being in constantly open communication with the suction line 22—comprising a passage 41 contained in a box structure 42 formed outwardly of the side wall 3 of the body and preferably integral therewith, the lower end of the passage 41 communicating with the antechamber 13 by an opening 43 through the side wall 3. The upper end of the passage 41 enters a recess 44 formed in the structure 42 and communicating with the discharge chamber 11 by an opening 45 through the body side wall 3. The opening 45 is controlled by a conventional refrigerant safety valve comprising a valve disc 46 operatively seated upon the margin of the opening 45 and resiliently retained thereupon by an adjustable spring

actuated mechanism 47 housed in a bonnet 48 removably secured to the structure 42 as by cap screws 49. Upon the building up of excessive pressure in the chamber 11, or in the high pressure side of the system with the stop valve 22 normally open, the disc 46 is automatically unseated and the excessive pressure is relieved by discharge through the passage 41 into the suction or low side of the system.

In making repairs to expansion coils or return lines of the refrigerant circulating system, it is necessary only to close a valve commonly provided between the condensed liquid receiver and the expansion coils and pump the refrigerant out of the suction or low side of the system over into the condenser and liquid receiver by the operation of the compressor with the control connections in normal operating relation. If repairs are to be made upon the condenser or other part of the so called high side of the system, it becomes necessary to reverse the normal control connections and operate the compressor to pump the refrigerant out of the high side into the low or suction side of the system, after closing a line valve as above mentioned. To accomplish this end I have provided two by-pass passages incorporated in the manifold body structure.

A passage 50, formed in the box structure 42, communicates at its upper end with the discharge chamber 11 by an opening 51 through the side wall 3, its lower end terminating in a port opening 52 leading into the lower portion of the passage 41 and thence through the opening 43 into the antechamber 13. The port opening 52 is controlled by a conventional hand valve 53 suitably secured in the structure 42 and having a valve disc 54 operatively seated upon a marginal valve seat provided about the opening 52. A passage 55, provided in a similar box structure 56 formed upon the opposite side wall 4 of the body, communicates at its upper end with the intermediate or oil trap chamber 14 and discharge line 20 by the opening 57 through the wall 4, the lower end of the passage communicating with the suction chamber 12 by the opening 58 through the wall 4. The passage 55 is intermediately divided by an intercommunicating port opening 59, the latter being controlled by a conventional hand valve 60 suitably secured in the structure 56 and having a valve disc 61 operatively seated upon a marginal valve seat provided about the opening 59.

In normal operation, the stop valves 22 and 23 are in open position and the by-pass valves 53 and 60 are closed. In order to pump out the high sides of the system, the stop valves 22 and 23 are closed and the by-pass valves 53 and 60 are opened. Then, communication between chambers 11 and 14 is closed, as is also closed the normal communication be-

5 between chambers 12 and 13. But, the suction chamber 12 then is in communication with the discharge line 20 through the passage 55, and the oil trap chamber 14, while the discharge chamber 11 is in communication with the suction line 22 through passages 50 and 41 and the antechamber 13, thus enabling the pumping of the refrigerant out of the discharge line into the suction line by the normal operation of the compressor.

10 Provision for the mounting upon the manifold body of conventional gauges, for indicating pressure in the discharge line and in the suction line respectively, is made by the 15 pipe connection 62 entering the wall 3 and communicating with the oil trap chamber 14, and by the pipe connection 63 entering the outer wall of the structure 42 and communicating through the passage 41 with the 20 antechamber 13.

25 It will here be apparent that I have provided in a compact unitary manifold structure all of the functions necessary to the operating control of a refrigerant compressor, in accessible arrangement for convenient manipulation.

I claim as my invention:

30 1. A device of the class described, comprising a manifold body having a suction chamber, an antechamber, a discharge chamber and an oil trap chamber, and having a by-pass passage connecting said discharge chamber with said antechamber and a by-pass passage connecting said oil trap chamber with said 35 suction chamber, said body having a port interconnecting said suction chamber and said antechamber and a port interconnecting said discharge chamber and said oil trap chamber, said body having means for the connection of said suction chamber and said discharge chamber respectively with the suction port and the discharge port of a refrigerant 40 compressor, and having means for the connection of said antechamber and said oil trap chamber respectively with the suction line and the discharge line of a refrigerant circulating system, and valve means for severally controlling said by-pass passages and said interconnecting ports.

45 2. A device of the class described, comprising a manifold body having a suction chamber, an antechamber, a discharge chamber and an oil trap chamber, and having a pressure relief passage connecting said discharge chamber with said antechamber, a by-pass passage connecting said discharge chamber with said antechamber and a by-pass passage connecting said oil trap chamber with said suction chamber, said body having an inter- 50 communicating port between said suction chamber and said antechamber and a similar port between said discharge chamber and said oil trap chamber, said body having means for the connection of said suction chamber and said discharge chamber respectively with the suction port and the discharge port of a refrigerant compressor, and having means for the connection of said antechamber and said oil trap chamber respectively with the suction line and the discharge line of a refrigerant circulating system, and valve means for severally controlling said relief passage, said oil passages, said by-pass passages and said intercommunicating ports.

55 suction port and the discharge port of a refrigerant compressor, and having means for the connection of said antechamber and said oil trap chamber respectively with the suction line and the discharge line of a refrigerant circulating system, and valve means for severally controlling said relief passage, said by-pass passages and said intercommunicating ports.

60 3. A device of the class described, comprising a manifold body having a suction chamber, an antechamber, a discharge chamber and an oil trap chamber, and having a by-pass passage connecting said discharge chamber with said antechamber, a by-pass passage connecting said oil trap chamber with said suction chamber and an oil passage connecting said oil trap chamber with said suction chamber, said body having a port interconnecting said suction chamber and said antechamber and a port interconnecting said discharge chamber and said oil trap chamber, said body having means for the connection of said suction chamber and said discharge chamber respectively with the suction port and the discharge port of a refrigerant compressor, and having means for the connection of said antechamber and said oil trap chamber respectively with the suction line and the discharge line of a refrigerant circulating system, and valve means for severally controlling said by-pass passages, said oil passage and said interconnecting ports.

65 4. A device of the class described, comprising a manifold body having a suction chamber, an antechamber, a discharge chamber and an oil trap chamber, and having a pressure relief passage connecting said discharge chamber with said antechamber, a by-pass passage connecting said oil trap chamber with said suction chamber and an oil passage connecting said oil trap chamber with said suction chamber, said body having an intercommunicating port between said suction chamber and said antechamber and a similar port between said discharge chamber and said oil trap chamber, said body having means for the connection of said suction chamber and said discharge chamber respectively with the suction port and the discharge port of a refrigerant compressor, and having means for the connection of said antechamber and said oil trap chamber respectively with the suction line and the discharge line of a refrigerant circulating system, and valve means for severally controlling said relief passage, said oil passages, said by-pass passages and said intercommunicating ports.

70 5. A device of the class described comprising a manifold body having a suction chamber, an antechamber, a discharge chamber and an oil trap chamber, and having a valve-controlled oil outlet from said oil trap chamber.

ber, said body having a valve-controlled port interconnecting said suction chamber and said antechamber and a valve-controlled port interconnecting said discharge chamber and said oil trap chamber, said body having means for the connection of said suction chamber and said discharge chamber respectively with the suction port and the discharge port of a refrigerant compressor, and having means for the connection of said antechamber and said oil trap chamber respectively with the suction line and the discharge line of a refrigerant circulating system.

6. A device of the class described comprising a manifold body having a suction chamber, an antechamber, a discharge chamber and an oil trap chamber, said body having a valve-controlled port interconnecting said suction chamber and said antechamber and a valve-controlled port interconnecting said discharge chamber and said oil trap chamber, said body having means for the connection of said antechamber and said oil trap chamber respectively with the suction line and the discharge line of a refrigerant circulating system, and means in said antechamber for trapping scale entering said antechamber from said suction line.

7. A device of the class described comprising a manifold body having a suction chamber, an antechamber, a discharge chamber and an oil trap chamber, and having a valve-controlled oil outlet from said oil trap chamber, said body having a valve-controlled port interconnecting said suction chamber and said antechamber and a valve-controlled port interconnecting said discharge chamber and said oil trap chamber, said body having means for the connection of said suction chamber and said discharge chamber respectively with the suction port and the discharge port of a refrigerant compressor, and having means for the connection of said antechamber and said oil trap chamber respectively with the suction line and the discharge line of a refrigerant circulating system, and a screen positioned in said antechamber about the connection with said suction line for retaining scale entering from said suction line.

8. A device of the class described, comprising a manifold body having a suction chamber, an antechamber, a discharge chamber and an oil trap chamber, and having a by-pass passage connecting said discharge chamber with said antechamber and a by-pass passage connecting said oil trap chamber with said suction chamber, said body having a port interconnecting said suction chamber and said antechamber and a port interconnecting said discharge chamber and said oil trap chamber, said body having means for the connection of said suction chamber and said discharge chamber respectively with the suction port and the discharge port of a refrigerant compressor, and having means for

the connection of said antechamber and said oil trap chamber respectively with the suction line and the discharge line of a refrigerant circulating system, and valve means for severally controlling said by-pass passages and said interconnecting ports, and a screen positioned in said antechamber adapted to intercept scale entering said antechamber from said suction line.

In witness whereof I have hereunto attached my signature.

JOHN C. SCOVEL, JR.
